UNITED STATES PATENT OFFICE.

ANDREW L. KULICK, OF DETROIT, MICHIGAN.

SPARK-PLUG.

1,332,904.

Specification of Letters Patent.

Patented Mar. 9, 1920.

Application filed July 26, 1919. Serial No. 313,606.

To all whom it may concern:

Be it known that I, ANDREW L. KULICK, a citizen of the United States, residing at Detroit, county of Wayne, State of Michigan, have invented a certain new and useful Improvement in Spark-Plugs, and declare the following to be a full, clear, and exact description of the same, such as will enable others skilled in the art to which it pertains to make and use the same, reference being had to the accompanying drawings, which form a part of this specification.

My invention relates to an improvement in spark plugs, the object of which is to provide a spark plug simple in construction and inexpensive to build and so easily disassembled that without removing the plug in the cylinder or stopping the engine the central electrode may be withdrawn and cleaned and then reinserted in place.

In the drawings:

Figure 1 is a longitudinal sectional view of my improved plug assembled.

Fig. 2 shows a modification wherein the porcelain insulating core is formed of lateral halves with recessed tubular ends.

Fig. 3 is a detail view of the central electrode and insulating cap formed thereon.

Fig. 4 is a longitudinal section on the insulating core *b* shown in Fig. 1.

Fig. 5 is a sectional view of one of the halves of the core shown in Fig. 2.

Fig. 6 is a detail of the central electrode and insulating cap used in the modification as shown in Fig. 2.

Fig. 7 is a view of one of the modified insulating cores.

Similar letters refer to similar parts.

a and *a*² are male and female members of a metallic shell, said metallic shell being exteriorly threaded at each end to receive insulating cap *e* hereinafter referred to or to be screwed into the engine casing. *b* is the insulating core provided with a central longitudinal passageway *b*'. This insulating core may be glazed inside as well as out as the central electrode is not fastened or cemented therein but merely passed therethrough. This core is formed as here shown with an enlarged central portion and reduced end portions. *c* represents a suitable gasket about which there is no novelty. *d* and *d*² are ground terminals of the outer electrode of the metallic shell located at

opposite ends thereof. *e* is an insulating cap, bakelite is suggested but no claim is made to that material. *f* is the central electrode. Insulating cap *e* is molded or permanently secured to the central electrode *f*, said electrode being threaded or otherwise roughened the better to hold to the insulating material. *g* is a collar on the central electrode adapted to be received and seated in a slight depression in the lower extremity of the projecting sleeve *e*². Insulating cap *e* is internally threaded so as to be screwed onto either end of the metallic shell. It is likewise provided with an internally projecting sleeve *e*² surrounding central electrode *f* and insulating the same from the external electrode. Below the collar *g* and between said collar and flattened end of the insulating core is a gasket *h* of suitable material to withstand heat, and act as a non-conductor of electricity to form a gas tight joint when said electrode is passed through the central opening of said insulating core and the insulating cap is screwed down. *j* represents a lock nut and *k* is the terminal plug screwed on the exterior projecting end of the electrode *f*. The feed wire to the electrode is not shown but its method of attachment is a conventional one and there is no novelty therein.

Fig. 2 is a modification. The insulating core is cylindrically recessed at its outer reduced ends and provided with a central cylindrical longitudinal passageway through which the central electrode may be passed. Insulating core may be formed in halves as shown in Fig. 5 or in one piece as in Fig. 7. Central electrode *f* is carried by insulating cap *e* in a manner similar to that shown in Fig. 1. Lock nut *j* and terminal plug *k* are not shown, neither is the line wire from the electrical circuit. The insulating cap *e* in this modification, however, is provided with a substantially longer internally projecting sleeve *e*³ than is found in Fig. 1. This sleeve surrounds and is formed to the electrode in a manner similar to that of the comparatively short projecting sleeve found in Fig. 1. Sleeve *e*³ is recessed at its lower extremity to provide a seat for collar *g* on electrode *f*. A gasket *h* is inserted between the collar *g* and the face of the porcelain core. When the cap *e* carrying the electrode is screwed on the shell, the collar on

the electrode is firmly seated in the recessed end of the cap sleeve and a gas tight joint formed between said collar and the porcelain through the gasket.

- 5 It will be noted from the above that the spark plug here provided may be disassembled by unscrewing insulating cap *e* and withdrawing such insulating cap carrying with it the central electrode. This may be 10 done while the engine is running and without removing the plug from the engine.

In the case of collection of carbon or foul material on electrode *f* or its ground terminal or upon the porcelain insulating core 15 the withdrawal of the central electrode will break any carbon connection formed with the ground terminal and the deposit on the electrode will be cleaned off as the same is withdrawn from the porcelain core. If the 20 engine is left running a blast of gas forced through longitudinal opening *b'* of the insulating core will ordinarily wash out the same. Should the plug be so fouled that it fails to operate after cleaning as above, it 25 may be removed from the engine and reversed end for end. In the modification shown in Fig. 2, insulating core may be composed of halves *b*² and *b*³ cylindrically recessed at their reduced outer ends, as 30 shown, to receive internally projecting cylindrical sleeve *e*³ of the insulating cap *e*.

As will be seen, the extent of carbonization necessary in this modification for a short circuit would be very nearly impossible of attainment. The central electrode could be withdrawn in the manner described above in Fig. 1. In addition, in case of a break in one end of the porcelain core the plug might be withdrawn from the engine 40 and by reversing the position of the insulating halves a working plug would be the result.

This plug because of the fact that it can be cleaned without removing from the engine and while the engine is running would be particularly adaptable for airplane engine work.

Protected as the insulating core is by the use of a metallic shell, this plug would be 50 peculiarly adaptable to marine work.

Expansion of the central electrode due to heating would tend to tighten the gas joint between the gasket *h* and the flattened end of the core *b* rather than to open up 55 the same.

What I claim is:

1. In a spark plug, the combination with a metallic shell provided with a ground terminal at either end externally threaded at 60 each end, of an insulating core provided with a central longitudinal passageway, an insulating cap internally threaded adapted to be screwed on either end of said metallic shell, and a central electrode permanently carried by said insulating cap and adapted

to be passed through the central opening in said insulating core.

2. In a spark plug, the combination with a metallic shell formed of male and female halves externally threaded at their outer ends provided with ground terminals at said ends disposed in sparking proximity to a central electrode, of an insulating core carried by said shell, said insulating core formed with recessed outer ends and axial longitudinal passageway therethrough, an insulating cap internally threaded adapted to be screwed on either end of said metallic shell provided with a longitudinal internally projecting sleeve adapted to be disposed within said tubular recess of said insulating core, a central electrode permanently axially embedded within said insulating cap and sleeve and adapted to be passed through said longitudinal passage way of said insulating core. 85

3. In a spark plug, the combination with a metallic shell formed of male and female halves externally threaded at its outer ends of ground terminals at either end thereof disposed in sparking proximity to a central electrode, an insulating core adapted to be carried by said shell provided with a central longitudinal passageway therethrough, an insulating cap internally threaded and adapted to be screwed on either end of said metallic shell, the central electrode permanently carried by said insulating cap one end thereof projecting above said cap and threaded to receive a lock nut and terminal 100 plug connecting up the electric circuit feed wire, said insulating cap being provided with an axially disposed internally projecting sleeve surrounding said central electrode to where it enters insulating core and insulating it from the external electrode. 95

4. In a spark plug, the combination with a metallic shell formed of male and female halves externally threaded at their outer ends of ground terminals at either end thereof disposed in sparking proximity to the central electrode, an insulating core carried by said shell and provided with a cylindrical central longitudinal passageway therethrough, an insulating cap adapted to 110 be screwed on either end of said shell provided with an axial internally projecting sleeve recessed at its lower extremity, a central electrode disposed axially through said insulating cap and sleeve and permanently 115 carried thereby provided with a collar formed thereon adapted to seat in said recessed end of said sleeve, a gasket surrounding said electrode disposed between said collar and the end of the insulating core. 120

5. In a spark plug, the combination with a metallic shell formed of male and female halves externally threaded at the outer ends and provided with a ground terminal at either end disposed in sparking proximity 130

- to the central electrode of an insulating core carried by said shell seated in suitable gaskets, said insulating core provided with a central longitudinal passageway there- 5 through and reduced opposite end portions permitting clearance of said metallic shell, an insulating cap internally threaded adapted to be screwed on either end of said metallic shell provided with an axial inter- 10 nationally projecting sleeve recessed at its lower extremity, a central electrode formed and permanently carried within said insulating cap threaded or roughened as it passes therethrough to embed itself more firmly in the 15 insulating material provided with an externally projecting portion threaded and adapted to receive a lock nut and terminal plug for carrying a line wire, provided with a collar adapted to seat in the recessed lower 20 extremity of said insulating cap sleeve, a gasket adapted to be disposed between said collar and said insulating core.
6. In a spark plug, the combination with a metallic shell formed of male and female 25 halves externally threaded at their outer ends provided with ground terminals at said ends disposed in sparking proximity to a central electrode, of an insulating core formed of halves carried by said shell, said 30 insulating core formed with recessed outer ends and an axial longitudinal passageway therethrough, an insulating cap internally threaded adapted to be screwed on either end of said metallic shell provided with a 35 longitudinal internally projecting sleeve adapted to be disposed within said tubular recess of said insulating core, a central electrode permanently carried by and axially disposed within said insulating cap and 40 sleeve and adapted to be passed through said longitudinal passageway of said insulating core.
7. In a spark plug, the combination of an 45 insulating core provided with an axial longitudinal passageway therethrough, a screw cap provided with an axial internally projecting sleeve, a central electrode adapted to be passed through said passageway in said insulating core and permanently axially disposed in said screw cap and sleeve, a collar on said electrode, a gasket adapted to be interposed between said collar and the 50 porcelain core and to be firmly seated when said screw cap is screwed on said spark plug.
8. In a spark plug, the combination with a 55 metallic shell formed of male and female halves externally threaded at opposite ends and provided with ground terminals dis- 60 posed in sparking proximity to a central electrode of an insulating core composed of lateral halves with longitudinal tubular recessed ends reduced for clearance in said metallic shell, said insulating core provided 65 with a longitudinal passageway there- through, an insulating cap adapted to be screwed on either end of said metallic shell provided with an axially internally projecting sleeve adapted to be disposed within said tubular opening in said insulating core 70 with a provided clearance therein, a central electrode permanently carried by said insulating cap adapted to pass through said longitudinal opening in said insulating core, a collar on said electrode adapted to be seated 75 in a recess in the lower extremity of said cap sleeve, a gasket adapted to be interposed between said collar and the seat of said tubular recessed opening in said insulating core. 80
9. In a spark plug, the combination with a metallic shell formed of male and female halves externally threaded at their outer ends provided with ground terminals at their ends disposed in sparking proximity to a central electrode, of an insulating core provided with an axial longitudinal passageway therethrough terminating in enlarged cylindrical recesses at its ends, and an insulating cap provided with an axial internally projecting sleeve adapted to be disposed within said cylindrical recess, a central electrode embedded axially in said cap and sleeve and adapted to pass through the longitudinal passageway in said insulating 95 core, a collar on said electrode seated in the lower end of said cap sleeve, a gasket adapted to be interposed between said collar and said insulating core and held firmly in place with the screwing of said insulating cap on 100 the end of said shell.
10. In a spark plug, the combination with a metallic shell provided with a ground terminal adapted to receive a screw cap, of an insulating core composed of lateral halves 105 provided with a longitudinal passageway therethrough terminating in cylindrical recesses and an insulating cap provided with an internally projecting sleeve, a central electrode axially permanently disposed within said cap and sleeve and adapted to pass through said longitudinal opening in said insulating core, said cap sleeve adapted to be seated in said tubular recess of said core, a collar on said electrode seated in the lower 110 end of said cap sleeve, a gasket adapted to be interposed between said collar and the seat of said cylindrical recess forming a gas tight joint when said cap is screwed on the outer shell. 115
11. In a spark plug, an outer shell provided with a ground terminal, an insulating core provided with a longitudinal passageway therethrough, an insulating cap carrying a central electrode adapted to be passed 120 through said longitudinal passageway in said insulating core, a collar on said electrode, a gasket abutting said collar, said cap adapted to be screwed on said outer shell seating said gasket and electrode collar 125 130

firmly against said insulating core for the formation of a gas tight joint.

12. In a spark plug, an insulating core provided with a longitudinal passageway adapted to receive an electrode, an insulating cap adapted to be screwed on said spark plug, an electrode carried by said insu-

lating cap, a gasket adapted to surround said electrode and form a gas tight joint between the external end of said insulating core and said cap when the cap is screwed on said plug. 10

ANDREW L. KULICK.
